UNITED STATES PATENT OFFICE.

WILLIAM H. EMMERT, OF CHICAGO, ILLINOIS.

GAME DEVICE.

1,345,914.

Specification of Letters Patent.

Patented July 6, 1920.

Application filed July 15, 1919. Serial No. 310,878.

To all whom it may concern:

Be it known that I, WILLIAM H. EMMERT, a citizen of the United States, and a resident of the city of Chicago, in the county of Cook and State of Illinois, have invented certain new and useful Improvements in Game Devices; and I do hereby declare that the following is a full, clear, and exact description of the same, reference being had to the accompanying drawings, and to the numerals of reference marked thereon, which form a part of this specification.

This invention relates to game devices in which a ball is allowed to roll down an inclined surface and the players score according to the position on the board where the ball stops.

One of the objects of the invention is to provide an improved device for carrying out an indoor game played with a ball.

Another object of the invention is to provide improved means for releasing a ball in devices of this type.

Other and further important objects of this invention will be apparent from the disclosures in the drawings and specification.

The invention in a preferred form is illustrated in the drawings and thereafter more fully described.

On the drawings:

Figure 1 is a perspective view of the device as a whole.

Fig. 2 is a plan view of the device on an enlarged scale with the center part broken away.

Fig. 3 is a section on the line 3-3 of Fig. 2.

Fig. 4 is a vertical section through the ball magazine.

Fig. 5 is a section on the line 5-5 of Fig. 3.

As shown on the drawings:

The device comprises a flat board 1 provided with one or more legs 2 at one end and shorter legs 3 and 4 at its opposite end, so that the board as a whole is inclined. Around the sides and lower end of the board is arranged a thin strip of wood or other material 5 to provide a retaining wall for preventing the balls by which the game is played from running off the board.

At the upper end of the board is provided a magazine for holding the balls 25 by which the game is played and also the mechanism for discharging these balls onto the board one by one. This magazine may con-

veniently be formed from a block of wood 6 suitably secured to the upper end of the board 1. In this block a vertical passageway 7 is formed which communicates with an inclined passageway 8 leading to a discharge aperture 9. The passageway 8 is offset with respect to passageway 7 as shown in Fig. 3 and a ridge or projection 10 is provided in the aperture which connects the passageways normally to prevent the balls 25 arranged in the passageway 7 from passing into the passageway 8.

The discharge of the balls into the passageway 8 may be brought about in various ways. In the form of construction shown, this is accomplished by means of a pin or plunger 11 secured to a disk 12 pivotally attached at 13 to the lower edge of the block 6. This pin 11 passes through an aperture 14 arranged in the front wall of the block 6 at such a height that it can push the lowermost ball over the ridge or projection 10 into the passageway 8. Normally this pin is held in retracted position by means of a spring 15 therearound. A lug 34 is provided on the lower margin of the disk 12 to prevent the disk falling down onto the board 1. If, however, the front of the disk 12 is struck the pin is projected inwardly to discharge one of the balls.

Preferably this disk is struck by means of a ball thrown thereagainst by means of a spring-actuated plunger 16 slidably arranged in a recess 17 in the leg 3 of the device. This plunger 16 is retracted by means of its operating pin 18 against the pressure of the spring 19 and then suddenly released, whereupon the ball in front of the plunger is thrown along a groove 20, arranged in the surface of the board 1, toward the disk 12 with sufficient force to cause the pin 11 to eject one of the balls 25.

In order that the ball provided for actuating the disk 12 shall automatically return to the recess 17 for further use a guiding and retaining wall 21 is arranged on the upper surface of the board on one side of the groove 20, while on the opposite side thereof a similar guiding and retaining wall 22 is provided. These walls guide the ball, as it drops after engagement with the disk 12, back into the groove 20, and thence into the recess 17. It will be observed that the discharge aperture 9 for the balls 25 is arranged to one side of the disk 12 and the retaining wall 21 so that there is no inter-

ference by these parts with the passage of the balls 25 down the board 1.

Toward the lower end of the board are arranged a series of groups of pins 23, the 5 majority being arranged in pairs although three or more pins may be included in one group if so desired. The players score according to the position which the ball is in when it comes to rest. Thus if a ball 10 strikes the uppermost pair of pins and is held thereby, the player scores 100, if it rebounds off these pins and strikes either pair of pins adjacent thereto and is held thereby the player scores 50, and so on. Similarly 15 if a ball is not retained by any of the pins and continues to roll until it reaches the rear retaining wall the player may be given any desired predetermined score.

I am aware that numerous details of construction may be varied through a wide 20 range without departing from the principles of this invention, and I therefore do not purpose limiting the patent granted otherwise than necessitated by the prior art.

25 I claim as my invention:

1. A game device comprising a board, a series of ball engaging devices thereon, and a magazine for holding a series of balls, said magazine comprising two offset passages, a 30 connecting passage having a ridge therein adapted normally to prevent the balls in the first passage passing into the second passage, and means for moving a ball through said connecting passage when desired.

35 2. A game device comprising a board, a series of ball engaging devices thereon and a magazine for holding a series of balls comprising a substantially vertical passage, an inclined passage offset relatively thereto, 40 a connecting passage having a ridge therein adapted normally to prevent the balls in the vertical passage passing into the second passage, and means for moving a ball through said connecting passage when desired.

45 3. A game device comprising an inclined board, a series of groups of pins thereon and a series of balls adapted to lodge against one or other of the groups of pins while rolling

down the board, a magazine adjacent the 50 upper end of the board for holding said balls, a pivotally mounted member provided with means for discharging the balls singly from the magazine, and means for projecting a ball against said member to cause the 55 discharge of a ball from the magazine.

4. A game device comprising an inclined board, a series of groups of pins thereon, a series of balls adapted to lodge against one or other of the groups of pins while 60 rolling down the board, a magazine adjacent the upper end of the board for holding said balls, a pivotally mounted member provided with means for discharging the balls singly from the magazine, a runway along one 65 side of the board leading to said member and means for projecting a ball up said runway against said member to cause the discharge of a ball from the magazine.

5. A game device comprising a board, a 70 series of ball engaging devices thereon and a magazine for holding a series of balls, said magazine comprising two offset passages, a connecting passage having a ridge therein adapted normally to prevent the balls in the 75 first passage passing into the second passage, means for moving a ball through said connecting passage when desired, and means for pushing the balls in the first passage one by one over said ridge.

6. A game device comprising a board, a series of ball engaging devices thereon and a magazine for holding a series of balls, said magazine comprising two offset passages, a connecting passage having its lower 80 surface formed and inclined so as normally to prevent the balls in the first passage passing into the second passage, and means for moving a ball through said connecting passage when desired.

90 In testimony whereof I have hereunto subscribed my name in the presence of two subscribing witnesses.

WILLIAM H. EMMERT.
